COMBINED ESCUTCHEON PLATE AND DOORKNOB

Roy Stuart Denker, Redondo Beach, Calif., assignor to
Schlage Lock Company, a corporation

Filed May 23, 1961, Ser. No. 65,298

Term of patent 14 years

(Cl. D50—3)

FIG. 3

FIG. 4

FIG. 1

FIG. 2

FIG. 1 is a front elevation of a combined escutcheon plate and doorknob showing my new design.

FIG. 2 is a side elevation.

FIG. 3 is a top plan view.

FIG. 4 is a cross section taken along lines 4—4 of FIG. 1.

I claim:

The ornamental design for a combined escutcheon plate and doorknob, as shown.
